Inventor
D Walton Burnett Wilson,
By his Attorney
Geo. F. Mather,

UNITED STATES PATENT OFFICE.

D WALTON BURNETT WILSON, OF STAMFORD, CONNECTICUT.

WRENCH.

1,367,222.

Specification of Letters Patent.

Patented Feb. 1, 1921.

Application filed April 28, 1920. Serial No. 377,161.

To all whom it may concern:

Be it known that I, D WALTON BURNETT WILSON, a citizen of the United States, and a resident of Stamford, county of Fairfield, 5 and State of Connecticut, have invented certain new and useful Improvements in Wrenches, of which the following is a specification.

My improvements relate to wrenches of 10 the so called "monkey" type, each formed with a fixed spanner stock jaw and with a movable clamping sleeve jaw; and the invention consists in the specific construction and arrangement of parts described and 15 claimed, a distinctive feature being the formation of the movable clamping sleeve jaw with a convexly curved segmental ratchet rack, for engagement with the stock rack, in conjunction with a spring on said movable 20 jaw which tends constantly to hold said racks in engagement, and to cause the clamping jaw to function as a spring jaw to pinch and dog the article clamped, all as hereinafter fully set forth.

25 In the accompanying drawings,

Figure 1, is a side elevation of my improved wrench, with the outline of a circular object positioned between its jaws;

Fig. 2, is a rear edge elevation of the 30 main part of the wrench;

Fig. 3, is a sectional elevation, the section being taken upon plane of line 3—3, Fig. 2, with the parts in the position shown in Fig. 1;

35 Fig. 4, is a similar section showing the movable jaw held with its ratchet rack out of engagement with the stock rack;

Fig. 5, is an end elevation of the wrench, looking in the direction indicated by the 40 arrow.

I have herein shown my invention as embodied in what is technically known as a pipe wrench, the jaws being provided with gripping teeth for engagement with the 45 peripheral surface of an object circular or otherwise curved in cross section, although I do not limit myself in this respect, as my improvement is applicable to monkey wrenches generally.

50 A, is the spanner or hand lever, formed with the fixed stock jaw or head a, having (in the present case) the gripping teeth a', the inner edge of said spanner lever A, being also formed with the rack teeth a'', prefer- 55 ably of barb shape as shown.

In Figs. 1 and 3, the circle P, represents

the outline of a pipe or other object to be clamped.

C, is my movable spring clamp jaw, formed in the present case with the gripping 60 teeth c, which are preferably arranged in slightly concave shape forming the biting edge of the jaw. The body portion c², of my spring clamp jaw C, is formed with a convexly segmental series of ratchet rack teeth 65 c³, adapted to engage with the spanner rack teeth a², as shown more particularly in Fig. 3, of the drawings, said ratchet rack teeth c³, being held in contactual engagement with said spanner rack teeth a², normally 70 by a dog spring s, positioned on an extension loop c⁴, of the body portion c², of the jaw, and bearing against the rear edge of the spanner lever A.

In Fig. 3, the circle 1, represents the axial 75 center of the segmental rack c³, and the line 2, the center line of fulcrum action between the parts,—the dog spring s tending constantly to rock the movable jaw C, in the direction of the arrows 3 and 4, thereby 80 causing the biting edge and teeth c, of the jaw C, to press against and pinch the peripheral surface of an object P, positioned between said movable jaw C, and the head or stock jaw a, of the spanner A.

c⁵, is an auxiliary loop extension of the body portion c², of my movable spring-clamping jaw C, which aids in supporting the same laterally upon the spanner lever A.

When it is desired to adjust my movable 90 spring jaw C, upon the spanner lever A, in either direction it is tilted over by hand as indicated in Fig. 4, so as to disengage its segmental ratchet teeth c³, from the stock 95 rack teeth a². By this means the bearing surfaces a', and c, may be proximately applied to the peripheral surface of an object P, to be clamped and manipulated,—the manual release of my spring clamp jaw C, under such circumstances allowing the dog 100 spring s, to interlock the rack teeth and rock the jaw C, on the fulcrum line 2, in such manner as to pinch the article P, as hereinbefore set forth, and thereby lock the wrench firmly in position thereon.

105 What I claim as my invention and desire to secure by Letters Patent is,

1. A wrench of the character designated, comprising a spanner lever formed with a head jaw, and with stock rack teeth, and a 110 movable jaw formed with a convexly segmental series of ratchet rack teeth engage-

able with said stock rack teeth, and also with a single dog spring so positioned on said movable jaw and acting on the outer face only of the spanner lever as to tend 5 constantly to hold both sets of rack teeth in engagement, and to rock said movable jaw on its said convexly segmental series of ratchet rack teeth in such manner as to pinch an article interposed between the wrench 10 jaws when the lever is swung in a clockwise direction, for the purpose set forth.

2. A wrench comprising a spanner lever with rigid toothed jaw and rack teeth, and a movable jaw having article-engaging portion 15 for coöperation with the fixed jaw and having its body portion formed with a con-

vexly segmental series of teeth, said movable jaw having loop extensions loosely embracing and receiving the spanner, and a spring in one only of said loops bearing 20 against the outer face of the spanner and tending to rock the movable jaw to hold the segmental teeth thereof in engagement with the teeth of the spanner to press the acting edge of the movable jaw against and pinch 25 an object between such acting edge and the teeth of the fixed jaw when the lever is swung in a clockwise direction.

D WALTON BURNETT WILSON.
